(57) CLAIM

The ornamental design for furniture side panel, as shown and described.

DESCRIPTION

1. Furniture side panel

1.1 : Perspective

1.2 : Enlarged

The design shows a furniture side panel with an actuating-arm drive for furniture flaps with a setting scale; view 1.2 is an enlarged view of the scale of view 1.1, the enlarged view 1.2 being taken from the left side under the actuating-arm drive; broken lines in view 1.2 indicate matter for which protection is not sought.
